J. W. BENNETT.

REINFORCING OF CONCRETE POSTS AND THE LIKE.

APPLICATION FILED MAR. 18, 1918.

1,334,881.

Patented Mar. 23, 1920.

19 10 Inventor:
Jackson W. Bennett.
By L. J. Fletcher Atty.

UNITED STATES PATENT OFFICE.

JACKSON W. BENNETT, OF CARTHAGE, MISSOURI.

REINFORCING OF CONCRETE POSTS AND THE LIKE.

1,334,881.

Specification of Letters Patent. Patented Mar. 23, 1920.

Application filed March 18, 1918. Serial No. 223,150.

To all whom it may concern:

Be it known that I, JACKSON W. BENNETT, a citizen of the United States of America, and a resident of Carthage, in the county of 5 Jasper and State of Missouri, have invented certain new and useful Improvements in Reinforcing of Concrete Posts and the like, of which the following is a specification.

The primary object of this invention is to 10 provide an improvement in the construction of reinforced concrete posts.

Another object of this invention is to provide an improvement in the manner of reinforcing a concrete post, in which the reinforcing members will be under compressional strains, thereby binding and gripping the concrete body of a post, the purpose of 15 the reinforcing members not only being to assist in stiffening the concrete body, but 20 more for the purpose of drawing and holding the concrete body together.

Other and further objects will appear in the specification and be specifically pointed out in the appended claim, reference being 25 had to the accompanying drawings exemplifying the invention, and in which,

Figure 1 is a front elevation of this improved post showing the fence securing strip secured thereto.

Fig. 2 is a longitudinal section taken 30 through this improved concrete post, showing said post in the mold.

Fig. 3 is a longitudinal section taken approximately on the line III—III of Fig. 2.

Fig. 4 is a fragmentary section taken on 35 the line IV—IV of Fig. 3.

Fig. 5 is a transverse section taken on the line V—V of Fig. 2.

Referring to the drawings, this improved 40 post comprises a reinforced body of concrete 1 or other self hardening material, and embedded in said body of concrete are a pair of compressional members 2, and as shown in Figs. 2 and 3 of the drawings which pertain to the molding of the post, said members 2 are secured to the metallic rods 3 and 4 and to the tightening wire 5. As shown these rods 3 and 4 have their ends 45 projecting from the sides of the post so as to form projections which tend to hold the post in the ground.

As shown in Figs. 2 and 3 during the construction of this improved post, the rods 3 and 4 are first mounted in horizontally arranged positions, their ends engaging their

respective notches 6 which are formed in the side walls 7 of the mold 8.

These compressional members 2 are constructed of barbed wire or the like, one end of one of the members 2 being secured to the rod 4 and is then stretched lengthwise in the mold and passed through the loop 9 of the tightening wire 5, then rearwardly and over and around the upper rod 3 and secured thereto, or can be extended to the lower rod 4 so that it will be engaged against said lower rod adjacent the opposite end to which the wire was originally engaged, said wire then being returned in the mold to the loop 9 of the tightening wire 5, then rearwardly again to the top rod 3 and secured thereto as designated at 10. The tightening wire 5 is extended through the opening 11 of the head mold end piece 12 and secured to the tightening member 13 which extends through the brace portion 14, the extended end of said tightening member 13 being threaded and having a nut 15 mounted thereon.

When the compressional member 2 has been mounted in the mold as just related, the tightening nut 15 is engaged and manipulated so that the tightening member 13 will be drawn, thereby exerting a pull on the wire strands of the members 2 and drawing them to the required tightness. A fibrous securing strip 16 triangular in cross section is laid with one of its faces engaging the bottom 17 of the mold in the approximate position as shown in Fig. 2, there being a pair of holes 18 formed in said strip, each hole being for the reception of a bolt 19, said bolts having their threaded ends extend above the side walls 7 of the mold. The end piece 20 is then mounted 95 against the ends of the mold side walls 7 and the mold is ready for the reception of the body of plastic material as shown in Fig. 2.

After the plastic material forming the 100 body portion 1 of the post has set, the tightening member 13 is released and disconnected from the tightening wire 5 and the head piece 12 is shifted from the top of the post so that the tightening wire 5 can be 105 clipped close to the top of the post at a point as designated at 21. Nuts 22 are then mounted on the threaded ends of the bolts 19 and the post is ready for use.

From the aforesaid description, it is to be 110

noted that when the looped wires comprising the compressional reinforcing members 2 were tightened prior to the filling in of the plastic material, said members 2 were then under tension and were so held during the setting of the plastic material around said members 2, said members on account of their being secured to the rods 3 and 4 and tightening wire 5 being in the form of loops 10 or bands.

Therefore, after the plastic material has set and the post is made, and the tightening wire 5 is cut, said members 2 will tend to release from their prior tensionally held 15 positions, thereby applying compressional strains to the set body of concrete in which they are embedded, and are therefore binding and compressional members rather than stiffening members.

20 In the use of this improved post, the securing strip 16 is then in position to receive the fence securing members such as nails, staples and the like.

If desired, the compressional reinforcing 25 members 2 can be secured and looped independently from the rods 3 and 4 as against

the afore related returning and interlacing of the wire.

If desired, the fibrous securing strip 16 and the extending bolts or rods 19 carried thereby can be secured to the bottom 17 of the mold, thereby forming a permanent part of the mold, so that after the post has been molded, a triangular recess and bolt holes will be provided in the mold for the reception of a removable triangular shaped nail or securing strip.

What I claim is:

A fence post comprising a body formed of cement and having a pair of transversely 40 arranged rods in its lower end, said rods being spaced apart and having their ends projecting from the post, a wire vertically arranged in the upper end of the post and having a loop at its lower end, and strands 45 of wire within the post and extending under tension from the bars through the loop on the vertical wire and back to the rods, the parts connected with the rods being spaced apart so that the wire strand assumes the 50 shape of a V.

JACKSON W. BENNETT.
